UNITED STATES PATENT OFFICE.

ERNEST O. SEITZ, OF DETROIT, MICHIGAN, ASSIGNOR TO C. M. HALL LAMP CO., OF DETROIT, MICHIGAN, A CORPORATION OF MICHIGAN.

COMBINED TAIL LIGHT AND STOP SIGNAL.

Application filed March 26, 1923. Serial No. 627,909.

The invention relates to vehicle lamps and has for its primary object the obtaining of a simple construction of combined tail light and stop signal as hereinafter set forth.

5 In the drawings:

Figure 1 is a perspective view of the lamp;

Figure 2 is a front elevation partly in section;

10 Figure 3 is a central longitudinal section,

A is the casing of any suitable form and provided at its front with the removable cover B. C is a socket projecting from the rear of the casing for receiving a connector plug, and D is a lamp socket within the casing for receiving the bulb E constituting the tail light.

To arrange the stop signal in the same casing with the tail light, a second lamp socket F is provided, this being preferably arranged adjacent to the top wall of the casing. G is an inner casing surrounding the socket F and extending forward to the cap B so as to prevent the passage of light between the compartments for the two bulbs. The casing G is preferably of segmental form so as to conform to the shape of the outer casing and its outer end is flanged at G' having a felt gasket G² for bearing against a liner plate H. The plate H secures in place the glass panels or lenses I and J and if desired the letters for the word "Stop" may be cut in a portion of the plate registering with the casing G.

25 The sockets D and F are preferably mounted on an insulator block K, which is secured by the screws L to the lining plate L' adjacent to the rear wall of the casing A. The plate L' in turn is secured to the casing A and is provided with studs M projecting rearward through apertures in the casing A, constituting means for mounting said casing upon its support. The socket member C has arranged therein two insulated spring contact members N and N' which project forwardly through apertures in the block K. The contact N' is positioned to register with the insulated contact of the bulb E, while the contact N engages a conductor strip O leading 40 into the lamp socket F and engaging the insulated contact member of the bulb for said socket. The sockets D and F are grounded upon the casing and thus each lamp bulb is provided with an insulated contact and a

grounded contact for completing the electric circuit.

The parts constructed as thus far described are assembled as follows: The socket C is secured to the lining plate L' by a flange C' engaging a countersunk portion of said plate. The insulator block K is then attached to the plate by clamping screws P and the casing G is sleeved upon the socket F and attached to the insulator plate by screws Q. The liner plate L' with the members attached thereto is then inserted within the casing A, the socket C projecting through an aperture in the rear wall of the case and being secured by a collar R having a threaded engagement with a portion of the socket. The cap B may then be attached by any suitable means, such as the screws S, which completes the assembly.

In operation, the electric circuits can be completed through the respective bulbs E by connections with the contact members N and N' and the usual controlling switches (not shown). Normally only the bulb E is illuminated, the rays of which extend through the lens J and also through the window T in the bottom of the casing for illuminating the license number. The bulb in the socket F is only illuminated when the stop signal is to be given and this bulb is preferably of greater candle power so as to produce a brilliant signal.

The construction organized as described can be cheaply manufactured and serves the purpose of the two independent lamps which are generally used.

90 What I claim as my invention is:

1. In a vehicle lamp, the combination with an outer casing, of an insulator block detachably secured within said casing, a plurality of lamp sockets having insulated contacts mounted on said insulator block, a connector socket also mounted on said insulator block and projecting outward through an aperture in said casing, insulated terminal contacts within said connector socket, means for respectively connecting the insulated contacts of said lamp sockets with said insulated terminal contacts within said connector socket, contacts for each of said lamp sockets, means for grounding said contacts, an inner casing surrounding one of said lamp sockets, and a cap for said outer casing having transparent panels, one of which reg-

isters with the chamber within said inner casing.

2. In a vehicle lamp, the combination with an outer casing, of an insulator block detachably secured adjacent to the rear wall of said casing, a plurality of lamp sockets for separate lamp bulbs mounted on said insulator block, a lining plate having a counter-sunk portion, a connector socket having a flange engaging said counter-sunk portion and projecting outward through an aperture in said casing, insulated spring contact members within said connector socket which project forwardly through apertures in said insulator block, means for connecting said lamp sockets with said spring contacts including a conductor strip leading into one of said lamp sockets and engaging an insulated contact member adapted to be on the bulb for said socket.

3. In a vehicle lamp the combination with an outer casing and a lining plate, of an insulator block detachably secured to said lin-

ing plate, a plurality of lamp sockets mounted on said insulator block and secured to said lining plate, said lining plate, insulator block and lamp sockets being insertable in said casing as a unit, and means for securing said lining plate to said casing.

4. In a vehicle lamp the combination with an outer casing and a lining plate, of an insulator block detachably secured to said lining plate, a plurality of lamp sockets mounted on said insulator block and secured to said lining plate an inner casing surrounding one of said sockets and secured to said insulator block, said lining plate, insulator block, lamp sockets and inner casing being insertable in said outer casing as a unit, and studs on said lining plate projecting rearwardly through apertures in said outer casing constituting means for securing said lining plate to the outer casing and for securing said casing to its support.

In testimony wherof I affix my signature.
ERNEST O. SEITZ.
